UNITED STATES PATENT OFFICE.

JOHN CALVIN RACKLEY, OF ROBERT LEE, TEXAS.

WEIGHT-MOTOR.

No. 882,583.

Specification of Letters Patent. Patented March 24, 1908.

Application filed July 13, 1907. Serial No. 383,678.

To all whom it may concern:

Be it known that I, JOHN CALVIN RACKLEY, a citizen of the United States, residing at Robert Lee, in the county of Coke and 5 State of Texas, have invented a new and useful Weight-Motor, of which the following is a specification.

This invention relates to a motor for driving a fan for cooling rooms, halls and other 10 apartments. The object being to provide a simple, cheap and durable mechanism for revolving a fan by means of a cord and weight.

Another object of the invention refers to the winding mechanism wherein a drum on 15 which the cord is wound and the first gear wheel are independently rotatable in one direction on the winding shaft, the latter having keyed thereon two ratchet wheels which engage respectively, pawls on the drum and 20 on the gear wheel.

A further object of the invention relates to a brake and stopping mechanism applied to a convex disk fast on the fan shaft.

Referring to the accompanying drawings:—Figure 1 is a side elevation of the motor shown as operating a fan. Fig. 2 is a sectional view of the winding drum on the line 2—2 of Fig. 1. Fig. 3 is a sectional view on the line 3—3 of Fig. 2.

Similar numerals of reference indicate corresponding parts on all of the figures.

The motor is carried in a frame made in any desired way, but as shown in the drawing, the bottom plate 1 and the perpendicular 35 side plates 2 and 3 are integral and extend upwardly to the same height, the side plate 2 having an inwardly turned flange 4 to which one end of the top plate 5 is bolted, screwed or otherwise fastened. The opposite end of 40 the top plate 5 is turned down and similarly fastened to the inner face of the side plate 3. The top plate 5 projects beyond the side plate 2 and is bent upwardly at 6 to form an offset or lug 7 by means of which it is screwed 45 to a fixed base, in this case a ceiling. A separate piece 8 of similar shape is fastened to the other end of the top plate and to the ceiling to support that end of the motor frame.

An upward offset 9 is made in the top plate 50 near the bent portion 6 which is perforated for a vertical driving shaft 10 the lower end of which shaft passes through a bearing opening in the bottom plate 1 and projects a short distance beyond the frame where it is 55 squared for a winding crank or key (not shown).

Loosely mounted on the driving shaft 10 is a winding drum 11 having a flange 12 on its lower end, beneath which is a ratchet wheel 13 keyed to the shaft 10. The ratchet wheel 60 13 is held a short distance above the bottom plate by a bracket 14 fixed to said plate and having a perforation through which the driving shaft passes. A pawl 15 is pivoted to the flange 12 of the drum to engage the ratchet 65 wheel 13 when the shaft is turned to the left for revolving the drum to wind the cord 16 thereon and raise the weight 17.

Loosely mounted on the shaft 10 at the opposite end of the drum 11, but disconnected 70 therefrom, is the master gear wheel 18, held close to the end of the drum by a ratchet wheel 19 keyed to the shaft 10, to serve as a flange for retaining the cord on the drum. A pawl 20 is pivoted on the master gear 75 wheel 18 and engages the ratchet wheel 19 to cause the rotation of said master wheel when the shaft 10 turns to the right. When a key is applied to the shaft 10 and the latter turned to the left, the ratchet wheels 13 and 80 19 also turn, the one 13 engages the pawl 15 and revolves the drum, winding the cord 16 thereon and raises the weight 17. The other ratchet 19 slips past the pawl 20 and the master wheel remains at rest. After the 85 weight has been wound to its full height, and the key released the cord is drawn by the weight from the drum, rotating it to the right and carrying the pawl 15 with it. This pawl continues its engagement with the 90 ratchet wheel 13, turning the shaft 10 and the ratchet wheel 19 to the right also. Moving in this direction the ratchet wheel 19 engages the pawl 20 and in turn carries the master wheel 18 with it. 95

The shaft 21, mounted in the frame and from which power is taken, is parallel to the driving shaft and in this instance carries a fan 22 on an extension 23 reaching a suitable distance below the frame, the upper end of 100 which shaft has fixed thereto below the top plate 5 a small pinion 24.

Between the driving shaft 10 and the shaft 21 are a plurality of parallel vertical shafts journaled in the base plate 1 and the top plate 5. Each shaft carries alternately at its upper and lower end a small pinion 25 and a large gear wheel 26. These gears and pinions intermesh with one another, the gear wheel 18 on the driving shaft and the pinions 110 24 on the fan shaft in the well known manner to give the fan shaft a rapid rotation. Below

the pinion 24 on the shaft 21 is fixed a circular plate 27 with a convex under surface 28. Threaded in the left side frame 3 just below the disk is a thumb screw 29 by means of which the speed of the motor may be changed or stopped altogether as will be described later. Fixed to the shaft 21 above the bottom frame plate 1 is a collar 30 to which on opposite sides are fastened two flat springs 31 which extend upwardly at a slight curve to the disk 27 and are attached to a hub 32 on its under side. Midway the length of each flat spring 31 is fastened a weight 33 which cause the springs to bow outward by centrifugal force when the shaft 21 rotates and pull the disk 27 downwardly, the latter being loose on the shaft.

When the regulator 34 which comprises the disk, flat springs, weights thereon and collar, is in the position indicated in Fig. 1 and the thumb screw 29 bears against its under surface near the hub, the friction between the screw and the disk is sufficient to prevent the shaft 21 rotating. If the screw be backed out a short distance it will be released from contact with the disk and the motor will run if wound up, but the speed of rotation will depend on the distance the screw has been retracted, for as soon as the disk strikes the end of the screw as it is drawn downwardly by the centrifugal action of the regulator, the speed will be held constant at that point, so that the more the screw is withdrawn the greater will the speed of the motor be. The motor is stopped by moving the screw inwardly to its limit as is evident.

Having thus described the invention, what is claimed is:—

1. A motor comprising a train of gearing, having a power driving shaft at one end and a power delivery shaft at the opposite end, a drum and a gear wheel each loosely mounted on the driving shaft, a ratchet wheel keyed to

one end of the shaft and a pawl pivoted to said drum in engagement with the ratchet wheel, a second ratchet wheel keyed to the shaft near the opposite end and a pawl pivoted to said gear wheel in engagement with said second ratchet wheel, and a weighted cord attached to said drum adapted when wound thereon to operate the mechanism.

2. A motor comprising a train of gearing, having a power driving shaft and a power delivery shaft at opposite ends of said train, a winding drum having a flange on one end and loosely mounted on said driving shaft, a gear wheel loosely mounted on the same shaft in close proximity to and serving as a flange for the other end of the drum but having independent movement, ratchet wheels on opposite ends of said driving shaft a pawl on the drum and one on the gear wheel in engagement with the respective ratchet wheels, and a cord and weight attached to said drum.

3. A motor comprising a train of gearing, having a driving shaft, a drum and a gear wheel each loosely mounted thereon, a cord and weight attached to said drum, separate ratchet devices for connecting the shaft to said drum and to said gear wheel, and so disposed that when the shaft is turned in one direction the drum will be turned by one ratchet and wind the cord on the drum without operating the gear wheel and when the weight turns the drum in opposite direction it will turn the shaft and the latter through the other ratchet, rotate the gear wheel and the motor.

In testimony that I claim the foregoing as my own, I have hereto affixed my signature in the presence of two witnesses.

JOHN CALVIN RACKLEY.
